(57) CLAIM

The ornamental design for a container for cosmetics, as shown and described.

DESCRIPTION

The patent or application file contains at least one drawing executed in color. Copies of this patent or patent application publication with color drawing(s) will be provided by the Office upon request and payment of the necessary fee.

1. Container for Cosmetics
2. Container for Cosmetics
3. Container for Cosmetics
- 1.1 : Perspective
- 1.2 : Front
- 1.3 : Back
- 1.4 : Left
- 1.5 : Right
- 1.6 : Top
- 1.7 : Bottom
- 2.1 : Perspective
- 2.2 : Front
- 2.3 : Back
- 2.4 : Left
- 2.5 : Right
- 2.6 : Top
- 2.7 : Bottom
- 3.1 : Perspective
- 3.2 : Front
- 3.3 : Back
- 3.4 : Left
- 3.5 : Right
- 3.6 : Top
- 3.7 : Bottom

The black background color in drawings forms no part of the claimed design. The white areas surrounded by broken lines in the drawings depict portions of the container for cosmetics that form no part of the claimed design. All of the broken lines in the drawings form no part of the claimed design. The word mark "COSRX" shown in the figures is a registered trademark of COSRX Inc. The word mark "COSRX" forms part of the claimed design.
